UNITED STATES PATENT OFFICE.

CLEMENT SMITH, OF TOPEKA, KANSAS.

HERNIAL TRUSS.

1,095,743.

Specification of Letters Patent.

Patented May 5, 1914.

Application filed November 17, 1913. Serial No. 801,408.

To all whom it may concern:

Be it known that I, CLEMENT SMITH, a citizen of the United States, residing at Topeka, in the county of Shawnee and State 5 of Kansas, have invented certain new and useful Improvements in Hernial Trusses, of which the following is a specification.

My invention relates to hernial trusses of the general type illustrated in Patent No. 10 690,624, granted January 7, 1902, to L. A. Smith. Its object is to substitute for the upward loop of the arch wire at the back, a pad that is pivoted or hinged to the arch wire in such manner that it has lateral flexibility with relation to the arch wire while maintaining substantially a constant position lengthwise of the wire; also to improve generally upon the means for fastening the arch wire to the truss-pad, and specifically 15 to eliminate from such fastening device all loops or bends which would prevent the easy removal and application of the sleeve covering the arch wire, also to provide a simple, economical, strong, and durable fastening 20 device that can be easily adjusted, applied, and removed, and that eliminates as far as possible projections likely to catch in the wearer's clothing. And my invention comprises the parts, improvements, and combinations hereinafter set forth and claimed.

In the drawings accompanying and forming part of this specification and in the description of the drawings I have shown my invention in its preferred form and what I 25 deem to be the best mode of applying the principles thereof; but it is to be understood that within the scope of the appended claims, I contemplate changes in form, proportions, and materials, the transposition of parts, 30 and the substitution of equivalent members, without departing from the spirit of my invention.

Figure 1 is an elevation of a hernial truss made in accordance with the principles of 45 my invention, somewhat in diagram. Fig. 2 is a view from the rear of the rear portion of the arch wire and the pads secured thereto. Fig. 3 is a sectional view through the line 3 in Fig. 2. Fig. 4 is an enlarged view 50 of the front face of a pad in diagram and the front end of the arch wire, together with my improved fastening device, one of the screws being removed. Fig. 5 is a sectional view of the retaining plate through the line 55 5 in Fig. 4. Fig. 6 is a sectional view of the parts shown in Fig. 4 through the line 6

in Fig. 4. Fig. 7 is a face view of the front end of the arch wire. Fig. 8 is an end view of the centering and retaining nut.

Similar reference characters indicate like 60 or corresponding parts throughout the several views.

9 is a truss-pad of any suitable kind; 10 is the arch wire adapted to fit over the hip; and 11 is the sleeve covering the arch wire. 65

12 is a plate of any suitable form having at its lower end an elongated bearing, or loop, 13, embracing the arch wire at the back. 14 is a pad of hard rubber or any other suitable substance, of suitable form, secured 70 to said plate by any suitable means, as by the two screws 16, 16. The pad preferably overlaps the plate in all directions so as to protect the wearer from contact with the metal parts and projections. 75

Secured to the upper end of the plate is a stud 17 adapted to be engaged by the perforated end of the body strap 18. After the arch wire passes through the bearing 13 it is bent downwardly, as shown at 19, and to its 80 lower end is attached (preferably flexibly) a pad 20, adapted to bear against the body of the wearer back of the hip joint. This pad also has a stud 21 adapted to be engaged by the perforated end of the strap 22. Preferably the two body straps meet in front, as at 23, and continue thence to the pad 9 to which it is secured by means of the stud 25, substantially covering the fastening device. 85

The front end of the arch wire 10 is 90 flattened, as shown at 26, the front face of the flattened portion being preferably substantially in alignment with the front side of the normal or round portion of the wire, and it has a hole 27 therethrough. 95

28 is a retaining plate, preferably circular in contour and having its edge inturned, as shown at 29. It has a central opening 30, two oppositely disposed slots, arc shaped, near its periphery, and a slot 31 in its in-turned edge. The latter slot is adapted for the reception, by close and snug fit, of the arch wire, the front face of whose flattened end fits against the inner surface of the retaining plate. The holes 30 and 27 are 100 brought into register, the inner threaded end 36 of the stud 25 is passed therethrough, and the nut 37 is then screwed onto the threaded end, clamping the flattened end of the arch wire firmly between the nut and 105 the retaining plate. The face of the truss-pad is recessed, as shown at 33, for the re- 110

ception of the nut; and the nut is preferably round, at least as to that portion which engages in the recess, so that the parts that are held firmly with the nut may oscillate thereabout. The retaining plate, and with it the arch wire, the stud, and the nut, are secured to the truss-pad by means of two screws 34 which pass through the slots 32, 32 and into the pad. Obviously my fastening device may be applied to and removed from the truss-pad while the device itself is thus firmly secured to the arch wire.

By using the flattened end of the arch wire with the fastening device, I am able to remove the sleeve 11 from and apply it to the arch wire, without bending or otherwise disturbing the latter, and also without cutting or otherwise injuring the sleeve. This is of special advantage because it is often necessary or desirable, for sanitary reasons, for repairs, etc., to remove the sleeve. Also my fastening device may be adjusted, as indicated by the dotted outline 35 in Fig. 4, by oscillating the retaining plate and connected parts in the recess 33, such movement being permitted by reason of the slots 32 through which the retaining screws 34 engage. The adjustment is effected by slightly loosening the screws 34, then shifting the parts, and then screwing down the screws 34 firmly.

With regard to the upwardly extending back pad, it will be noted that the downward bend 19 prevents the pad from slipping longitudinally upon the arch wire, the bend forming a stop. The advantage of so mounting the upwardly extending back pad upon the rear of the arch wire so as to have forward and rearward oscillatory movement, is that by so doing this pad is made to conform automatically to the wearer and to the movements of his body without such strain on the arch wire as would displace it or cause undue binding on the wearer.

What I claim is:

1. In a hernial truss, the combination of an arch-wire having a flat front end and a hole through the flat portion, a truss-pad having a recess in its front face, a circular retaining plate having a centrally-disposed hole, two oppositely disposed arc-shaped slots near its periphery, having its outer edge inturned and having a slot in said inturned edge for the reception of the arch-wire, a stud having a screw-threaded inner end, said inner end extending through the centrally-disposed hole in the retaining plate and through the hole in the flat portion of the arch wire, a nut engaging said inner end for clamping the flat portion between the inner face of the retaining plate and the nut, said stud having a bearing against the outer face of said retaining plate, said nut engaging in said recess in the truss-pad, and

screws extending through the respective slots and secured in the pad.

2. In a hernial truss, the combination of a pad having a recess in its face, a nut engaging in said recess and extending outwardly from said recess, an arch-wire having a flattened end, a retaining plate having inturned edges bearing against the face of the pad and having a slot in one edge for the reception of said arch-wire, a screw extending through said retaining-plate, flattened end and nut for clamping the flattened end firmly between the retaining plate and the nut, and means for securing the retaining plate to the face of the truss-pad. 75

3. In a hernial truss, the combination of a truss-pad, a retaining plate, an arch-wire having a flattened end, said retaining plate being formed with means for preventing the arch-wire from having oscillatory movement with relation to said plate, a nut, a screw extending through said plate, said flattened end, and said nut for clamping the flattened end firmly between said nut and the inner face of the plate, and means for 80 securing the plate to the pad.

4. In a hernial truss, the combination of a pad having a pivot hole in its face, a nut pivotally engaging in said pivot hole and extending outwardly from said pivot hole, 95 an arch wire having a flattened front end and formed with a hole through the flattened portion, a retaining plate having inturned edges bearing against the face of the pad, having a slot in its inturned edge 100 for the reception of the arch wire, and having arc-shaped slots concentric with said pivot hole, a screw extending through said retaining plate and said hole in said flattened end and engaging said nut and clamping the flattened end between said retaining plate and said nut, and screws extending through said arc-shaped slots and into the pad for adjustably securing the retaining plate to the pad. 105

5. In a hernial truss, the combination of a truss pad, an arch wire having at the back a downwardly bent portion, a lower back pad secured to the lower end of said downwardly bent portion, an upper back pad pivoted to said arch wire at the back adjacent to said downwardly bent portion and extending upwardly from said arch wire and being so pivoted as to have oscillatory movement transversely of the length of the 115 portion of the arch wire to which it is pivoted and having no movement lengthwise of said portion, and body straps connecting the truss pad with the lower back pad and with the upper portion of said 120 upper back pad. 125

6. In a hernial truss, the combination of a front truss pad, an arch wire having a depending arm at the rear, a lower back pad secured to the lower end of said depending 130

arm, an upwardly extending arm pivoted at its lower end to the back portion of the arch wire adjacent to said depending arm and being so pivoted as to have oscillatory movement circumferentially of that portion of the arch wire to which it is pivoted and so as to be held against movement lengthwise of such portion, and body straps connecting the front truss pad with the lower back pad and with the upper portion of the upper back pad.

7. In a hernial truss, the combination of a pad having a pivot hole in its face, a nut pivotally engaging in said pivot hole, a retaining plate having a hole registering with said nut and having arc-shaped slots concentric with said pivot hole, an arch wire having a flattened front end with a hole

therethrough, a screw extending through said retaining plate hole and said hole in 20 said flattened end and into said nut and clamping the flattened end between the retaining plate and the nut, and screws extending through said arc-shaped slots and into the pad for adjustably securing the retaining plate to the pad, said retaining plate being formed with means for preventing movement of the arch wire with relation thereto when said flattened end is clamped as aforesaid.

In testimony whereof I have affixed my signature in presence of two witnesses.

CLEMENT SMITH.
